UNITED STATES PATENT OFFICE

JOHN F. A. DAVIS, OF WENHAM, MASSACHUSETTS

BUFFING WHEEL

Application filed October 20, 1927. Serial No. 227,442.

The invention relates to an improvement in buffing wheels of that type in which the wheel is provided with a removable covering of some abrasive material wrapped around the wheel and the ends of which are brought together, retained and the covering tightened by mechanism within the wheel.

The object of the invention is to provide improved mechanism inside the wheel for gripping and holding the ends of the abrasive covering, and especially a mechanism which will permit of the ends of the covering being drawn inwardly by the gripping mechanism after it has gripped the ends of the covering in order that the covering may then be pulled properly tight about the wheel.

The invention can best be understood by reference to the drawing in which—

Figure 1 is a side elevation of the buffing wheel embodying the invention, such portion only of the wheel being shown as is necessary for a proper understanding thereof.

Fig. 2 is also a side elevation of certain portions of the wheel.

Fig. 3 is a cross section of the wheel, and

Fig. 4 is a plan of the interior or working side of the cam, to which reference will later be made.

Referring to the drawing:—

1 represents the wheel of which 2 is its rim and 3 its body. The body is preferably made dished excepting for a diametric portion 4 of a thickness substantially equal to the width of the rim.

Wrapped around the rim of the wheel is a felt or cushion 5 and over this is laid an abrasive covering 6. This covering consists of a strip of sandpaper or other abrasive material in sheet form. In width it corresponds with the width of the rim but in length is longer than the circumference of the wheel with added felt cushion to permit of its ends 7, 7 passing through the cushion, thence through a radial slot 8 cut in the rim and into a chamber 9 within which the ends of the strip are gripped and held and the strip tightened on the wheel in a manner later to be explained.

The chamber 9 contains the gripping mechanism for the ends of the abrasive strip.

It is formed in the body portion 4 of the wheel adjacent the radial slot 8 in the rim. This chamber is normally closed by a cover 10 secured to the body portion 4 by screws 11 or in any other suitable manner.

55

The wheel is provided with an axial opening 12. Outside this opening a circular opening or cavity 13 is formed in the side of the body portion 4. This opening is centrally located and the wall of the body portion 4 surrounding the opening provides a central bearing for a rotary cam later to be referred to.

60

The gripping mechanism for the ends of the abrasive strip arranged in the chamber 9 comprises opposing jaws 15, 15. These jaws are pivotally retained by a pin 16 passed through the shanks of the respective jaws and through the clef end of a slide bar 17 on which the jaws are thus pivotally arranged to turn. The jaws are held in a normal open position out of engagement with the ends of the abrasive strip by means of a spring 18 common to both, this spring being passed around the pin 16 outside the end 70 of the bar 17 and connecting with the respective jaws.

70

The bar 17 is arranged to slide in a radial slot or way 19 formed within the body portion 4 of the wheel, the inner end of the bar entering the cavity 13 formed in the side thereof as aforesaid. Thus arranged the bar is movable in a radial direction with either a forward or reverse movement carrying with it the jaws 15, 15 of the grip.

85

Socketed within the cavity 13 in the body portion 4 of the wheel is a cam 20 having a spiral groove 21 cut in its inner side. Extending into this groove is a cam member 22 projecting from the outer side of the sliding bar 17, the arrangement being such that as the cam is turned in one direction or the other it will operate through the cam member 22 and sliding bar 17 to move the jaws 15, 15 of the grip inwardly or outwardly 90 within the chamber 9 in which they are contained.

90

The cam 20 is held in place by the flanged head 23 of a hub 24 which lines the axial opening 12 through the centre of the wheel.

100

The hub 24 is secured by screws 25 which fasten partly into the end thereof and partly into the body portion 4 of the wheel which surrounds the end of the hub. Thus retained by the head 23 of the hub the cam 5 will turn freely within the socket in which it is contained and to facilitate its turning the cam is preferably provided with one or more exterior openings 26.

10 Backing each of the jaws 15 of the grip is a coiled spring 27. These springs lie beneath the respective jaws seated within sockets 28 formed in the body portion 4 of the wheel. From their respective seatings 15 the springs extend upwardly with an inward inclination bearing against the under sides of the respective jaws, the bearing ends of the springs being retained by means of pins 29 projecting from the under sides of the 20 jaws and extending into the coils of the springs. The relative arrangement of the springs 27 is such that as the slide bar 17 is moved inwardly by the operation of the cam, drawing the jaws of the grip with it, 25 the jaws will be drawn to engage the springs 27, distorting them and causing them to exert pressure for closing the jaws and maintaining them in a closed position as long as the springs remain tensioned.

30 The general operation is as follows: It will first be assumed that the jaws 15, 15 of the grip have been moved outwardly within the chamber 9 in which they are contained by the turning of the cam so that the springs 35 27 are no longer active and the jaws are made to occupy their normal open position by the tension of the spring 18. The ends 7, 7 of the abrasive covering or strip 6 are then brought together and passed through the 40 slot 8 in the rim of the wheel, thence down into the chamber 9 of the wheel and between the open jaws of the grip. The cam 20 is now turned in a direction for drawing in the jaws of the grip, this action being consequent upon the drawing in of the slide bar 17 by 45 the cam as explained above. As the operation of the cam is continued the jaws of the grip will be brought to bear against the springs 27 compressing them and the springs 50 being thus distorted will exert pressure against the jaws of the grip closing them upon the ends 7, 7 of the abrasion strip. After the closing of the jaws upon the ends 55 of the strip the operation of the cam is continued to effect a further inward movement or drawing in of the grip. Inasmuch as the jaws of the grip are then closed upon the ends of the abrasive strip, consequently the ends of the strip will be drawn or pulled 60 in by the grip tightening the abrasive strip on the wheel, the operation of the cam being continued until the ends of the abrasive strip have been drawn in so far as to have made the strip to tightly hug the wheel or felt 65 covering. The action of the grip tending to

draw in the ends of the strip after its jaws have closed upon said ends is permitted by the tensional means or springs which operate to close the jaws. After these springs have effected a closure of the jaws upon the 70 ends of the abrasive strip a further inward movement of the grip is permitted from the fact that the springs which have closed the jaws and are maintaining them in a closed position may still be further compressed, 75 such action tending not only to exert a further tightening action upon the jaws, but more essentially permitting of such a further inward movement of the jaws or grip them in engagement with the ends of the abrasive strip as will properly tighten the strip around the wheel.

A reverse movement of the cam permits a release of the abrasive strip, the jaws of the grip first being moved outwardly loosening the strip, a further continued movement of the cam operating to move the jaws out so far that the springs 27 are no longer effective for closing the jaws when the jaws will be allowed to open releasing the ends of the abrasive strip which may then be removed for the purpose of renewal.

Having thus fully described my invention, I claim and desire to secure by Letters of the United States:—

1. A buffing wheel comprising the body of the wheel having within it a chamber open for receiving the meeting ends of an abrasive covering for the wheel, a grip having opposing jaws located within said chamber, an inwardly and outwardly movable grip carrier, means for pivotally securing the opposing jaws of the grip to the grip carrier whereby as the grip is moved inwardly both jaws may be moved laterally toward one another into engagement with said ends of the abrasive sheet and grip the sheet between them on bringing the jaws together, springs backing said jaws of the grip and arranged interposed, respectively, between said jaws and the bottom of said chamber within which the grip is contained whereby the springs will be tensioned by draft of the jaws as the jaws are moved inwardly by the carrier as aforesaid and thereby exert force to close the jaws for gripping the meeting ends of the abrasive sheet as aforesaid, and whereby also inward movement of the jaws and tensioning of the springs may be continued after the jaws have gripped said ends of the abrasive sheet as aforesaid, and means for moving the grip carrier inwardly or outwardly.

2. A buffing wheel comprising the body of the wheel having within it a chamber open for receiving the meeting ends of an abrasive covering for the wheel, a grip having opposing jaws located within said chamber, an inwardly and outwardly movable grip carrier, means for pivotally securing the opposing jaws of the grip to the grip carrier where-

- by as the grip is moved inwardly both jaws may be moved laterally toward one another into engagement with said ends of the abrasive sheet and grip the sheet between them
- 5 on bringing the jaws together, a spring engagement at least one of said jaws for holding them apart when the grip carrier is moved to its outward position, springs back-
ing said jaws of the grip and arranged in-
- 10 terposed, respectively, between said jaws and the bottom of said chamber within which the grip is contained whereby the springs will be tensioned by draft of the jaws as the jaws are moved inwardly by the carrier as afore-
- 15 said and thereby exert force to close the jaws for gripping the meeting ends of the abrasive sheet as aforesaid, and whereby also inward movement of the jaws and tensioning of the springs may be continued after the jaws have
- 20 gripped said ends of the abrasive sheet as aforesaid, and means for moving the grip carrier inwardly or outwardly.
